UNITED STATES PATENT OFFICE.

GEORGE FREDERICK BRACKETT, OF JERSEY CITY, NEW JERSEY.

TIMING APPARATUS.

SPECIFICATION forming part of Letters Patent No. 555,847, dated March 3, 1896.

Application filed March 14, 1895. Serial No. 541,776. (No model.)

To all whom it may concern:

Be it known that I, GEORGE FREDERICK BRACKETT, of Jersey City, county of Hudson, State of New Jersey, have invented certain 5 new and useful Improvements in Timing Apparatus, of which the following is a specification, reference being had to the accompanying drawings.

The object of my invention is to produce 10 apparatus adapted to measure uniform intervals of time for the operation of machinery. Although its employment is not confined to use in connection with the process of preparing asphaltic street mixtures, that is one of 15 the uses to which I propose to apply it, and I shall therefore, for the sake of explanation, briefly describe its application to that process.

Ordinary asphaltic street mixture is composed of sand, limestone-dust, and asphaltic 20 cement, which require to be intimately commingled and incorporated. The most approved means of producing the mixture is by machinery, in the use of which it is essential, in order to insure the best results, that the 25 commingling of the ingredients should be properly timed. In mixing the aforementioned ingredients it is customary to stir the sand and limestone-dust together for about twenty seconds, and afterward to add the asphaltic cement and mix the whole compound 30 for a minute. Heretofore it has been necessary to depend upon workmen to time the different mixing operations, but this method of timing has proved uncertain and is frequently 35 attended with evil results, owing to the carelessness or mistakes of the operator.

By my invention I provide for the measurement of uniform intervals of time required 40 and for the sounding of a bell-warning at the lapse of each interval. By this means not only is the liability of mistake on the part of the operator who has the work directly in charge almost entirely eliminated, but all the workmen engaged in the operation are equally 45 notified of the time intervals, so that a check is by the use of my invention placed upon the carelessness or inattention of the operator.

In the accompanying drawings, Figure I is a side elevation of my indicator and stop 50 mechanism. Fig. II is a front view thereof.

Fig. III is a view of a clock-starting mechanism detached. Fig. IV is a plan view of a portion of the stop mechanism. Fig. V is a side elevation of sections of conveyer-tracks, showing the electrical wiring of the same. 55 Fig. VI is a plan view of the same. Fig. VII is a group illustrating side and plan views of one conveyer-track. Fig. VIII is a similar view illustrating another form of track. Fig. IX is a diagrammatical view of the circuits. 60

Referring to the figures on the drawings, 1 indicates a dial made of suitable insulating material—as, for example, hard rubber—that is adapted to be revolved at any required rate of speed by the shaft 2, which is connected 65 with a suitable time-movement or driving mechanism.

3 indicates sockets, located preferably near the edge of the dial-plate.

4 indicates brass or other conductive metal 70 screws set in the face of the dial. The screws and the sockets are arranged close together in pairs, which are located at required distances apart in order to pass a given point at required intervals of time. Each of the 75 screws 4 is connected in circuit by wires 5 secured to the screws on the rear of the dial-plate by suitable means, and all of the screws 4 are likewise electrically connected to the case 6 of the clock, as by wires 7, secured to 80 any of the screws 4 at one end, respectively, and at their other ends to similar screws 4^a upon a hub 8 on the shaft 2.

9 indicates an electric wire, which connects the case 6 with the relay binding-post 10 and 85 thereby establishes communication between said binding-post and each of the screws 4 through the system of wiring just described.

11 indicates the base of the relay, and 12 its electromagnet, supported, as usual, upon 90 a bracket 13.

14 indicates the armature vibrating between adjustment-screws 15 and 16 that are carried by a standard 17. The screw 15 has an insulated or hard-rubber point. The armature is pivoted, as indicated at 18, to a metallic base 19, and is drawn toward the face of the dial-plate 1, as by a coil-spring 20, secured at one end, 21, to the armature and at the other end to a stud 22. The base 19 is 95 100

- connected, as by a wire 23, to the binding-post 10, and the standard 17 is connected by a wire 24 to a binding-post 25.
- 26 indicates a connecting-wire uniting the binding-post 25 to a binding-post 27.
- 28 indicates another wire connecting the binding-post 10 with the binding-post 29.
- The binding-posts 27 and 29 are secured to a base 30 and are in circuit with an electro-magnet 31.
- 32 indicates a lever-armature carried on a standard 33 and under tension of a spring 34 opposed to the force of the magnet 31.
- 35 indicates set-screws carried upon a standard 36 and between which the armature 32 vibrates. The longer end of the armature 32, opposite the spring 34, is provided with a yielding extension or spring extension 37, which, by the vibration of the lever 32, 20 wipes the periphery of the balance-wheel 38, which forms a part of the time-movement, of which the shaft 2 is also a part, and which is not otherwise illustrated in detail. Armature 32 and its connected mechanism I will term "start mechanism." The armature 14 is provided with a stop-pin 39 that, under the actuation of the spring 20, is adapted to enter successively at proper intervals the sockets 3. While in such engagement with one 30 of the sockets the dial-plate 1 is, of course, stationary, and the time-movement is also stationary. While the parts are in this position electric circuit is established from the contact point or screw 16 through the standard 17, wire 24, binding-post 25, wire 26, binding-post 27, magnet 31, thence from said magnet through the binding-post 29, wire 28, binding-post 10, wire 23, armature 14 and contact-pin 40 in contact with the screw 16, 35 whereupon the armature 32 is attracted by that magnet and assumes the position shown in full lines in Fig. III of the drawings. This represents the starting position before the measurement of an interval of time is begun.
- 42 indicates one binding-post, and 43 the other, which establishes communication to line-wires 44 and 45 and to the electromagnet 12. The wires 44 and 45 communicate, respectively, with insulated contact-plates 46 and 47, which, separated by a strip of insulating material 48 and located on top of a track-beam 49, constitute the terminal section of a trolley-track 50.
- 51 indicates a metal trolley movable on the track 50 and provided with wheels 52, which, when they ride upon the contact-plates 46 and 47, form electrical contact between them. The trolley carries a dumping-bucket 53 of any suitable construction and adapted to be operated by any suitable means. The contact-plates 46 and 47 are located directly over the mixing-machine, which may be of any ordinary suitable kind, and is not necessary to illustrate. Its location with respect to the mixer is designed to provide for the commencement of the timing interval from the

moment at which the dumper arrives above the mixer and its contents are dumped into the same. The mixer being in operation when it receives the dump from the bucket 53 that

moment of time determines when the mixing operation begins. Since, as above explained, in the manufacture of asphaltic street mixtures there are two sets of ingredients to be mixed separately and during different intervals of time, I provide, as shown in Figs. V and VI, two sets of trolley-tracks, the second 75 one being shown clearly in Fig. VI at 55.

56 indicates the wheels of a second trolley, 80 and 57 the bucket thereof.

58 indicates a bowed spring secured to the side of the track 55 and extending yieldingly in the path of the arm 59, which suspends the bucket 57. When, therefore, the arm 59 85 brushes over the spring 58, it forms contact between the track 60 on which the wheels 56 turn and the spring 58, those two parts being electrically connected by branch wires 61 and 62, respectively, with the wires 44 and 45. 90 The spring 58 is also located over the mixer, so that the discharge of either of the buckets 53 or 57 is adapted to begin the operation of the time-movement.

63 indicates suitable electric-bell mechanism that is operatively connected with the wire 9 and through it with each of the screws 4 on the dial-plate. The different sets of line-wires described are assumed to be connected respectively with a source of energy—as, for example, with a battery—which it is not deemed necessary to illustrate.

It will thus be seen that the embodiment of my invention, considered as an entirety, embraces three distinct yet somewhat interdependent electric circuits, which for convenience in drawing the claims, I will term, first, the "controlling-circuit," which comprehends the circuit opened or closed by the trolleys, and which serves when closed to magnetize 105 the electromagnet 12; second, the "starting-circuit" opened or closed by the armature 14, the make-and-break contact being between the point 40 and a screw 16, which circuit controls the operation of the armature 32, and, 110 third, an "alarm-circuit" opened or closed by the movement of the dial, the make-and-break contact-point being between the stop-pin 39 and any one of the contact-screws 4. The terms employed to designate these circuits are appropriate as descriptive of the 115 functions of the mechanisms which are actuated as each of them is respectively opened or closed.

The operation of my apparatus is as follows: 125 Supposing the armature 14 to be in the position shown in full lines in Fig. I, the dial-plate being held by the engagement of the stop-pin 39 with one of the sockets 3 and the movement of the time mechanism thereby arrested. The armature 32 will, as above suggested, be attracted by the magnet 31, as shown in full lines in Fig. III. Suppose now that either of the trolleys—for example, trol-

ley 51—rides upon the contact-plates 46 and 47. Thereupon circuit is made between the wires 44 and 45, the magnet 12 is magnetized and the armature 14 is attracted. By the 5 movement of the armature the pin 39 releases the dial-plate and at the same instant breaks contact between the point 40 and the screw 16, thereby breaking circuit through the magnet 31 and releasing the armature 32. That 10 armature being released the spring 34 swings it upon its support 33 and brushes the spring 37 against the periphery of the balance-wheel 38, thereby setting the time-movement in motion and causing the dial-plate 1 to rotate in 15 the direction of the arrow shown in Fig. II. After the bucket 53 has been dumped it is promptly returned upon the track 50 and the circuit between the wires 44 and 45 is broken. The movement of the dial-plate 1, however, 20 after being once started is independent of such contact and proceeds accordingly. The pin 39 on the armature 14 rubs against the face of the dial-plate 1 under the tension of the spring 20, and when it reaches the next 25 adjacent screw-head 40 makes circuit through the base 19 and wire 23 by the binding-post 10 and the wire 9, as in the manner above described, with the bell mechanism 63, which, during the contact of the pin 39 with a screw 30 4, continues to sound. Immediately beyond the screw 4 is a socket 3, so that as soon as the sound of the bell mechanism ceases the pin 39 drops into a socket 3 and arrests the rotation of the dial until it is liberated by circuit 35 being established in the manner above described between the wires 44 and 45. When the pin 39 slips into the socket 3, (but not before,) the point 40 again makes contact with the screw 16 and magnetizes the magnet 40 31, thereby attracting the armature 32 and setting it in position to start the balance-wheel when another time interval is to be measured. The spring extension 37 in its 45 backward sweep across the balance-wheel strikes its periphery, but does not injuriously affect it, its strength being very slight, since it is only necessary for it to be stiff enough to cause the extremely sensitive spring of the wheel to respond to its impulse.

50 The backward sweep of the flexible extension 37 across the balance-wheel cannot start the time-movement, because it is maintained in a fixed position by the engagement of the armature 14 with the dial-plate.

55 Through the operation of the above-described apparatus the working time of the mixer is accurately measured, and the intervals at which the different materials are to be fed to the mixer are announced by the alarm-bell.

What I claim is—

1. In timing apparatus, the combination with a time-movement and time-movement stop mechanism, of separate time-movement 65 start mechanism controlled by the stop mech-

anism and means for actuating the stop mechanism, substantially as specified.

2. In timing apparatus, the combination with a time-movement, of time-movement stop mechanism, and separate time-movement 70 start mechanism electrically connected with the time-movement stop mechanism, substantially as specified.

3. In timing apparatus, the combination with a time-movement and time-movement 75 stop mechanism, of time-movement start mechanism in electrical connection with the time-movement stop mechanism, and a controlling-circuit controlling the movement of the stop mechanism, substantially as speci- 80 fied.

4. In timing apparatus, the combination with a time-movement and time-movement stop mechanism, of separate dependent time-movement start mechanism, a controlling-circ- 85 uit controlling the stop mechanism, and a movable conductor designed to make and break the controlling-circuit, substantially as specified.

5. In timing apparatus, the combination 90 with a time-movement and time-movement stop mechanism, of separate time-movement start mechanism in an electric circuit opened or closed by the time-movement stop mech- 95 anism, a controlling-circuit controlling the movement of said stop mechanism, and a movable conductor designed to make and break the controlling-circuit, substantially as speci- fied.

6. The combination with a time-movement, 100 of time-movement stop mechanism and separate time-movement start mechanism connected in an electric circuit, said circuit being closed by the operation of the time-movement, substantially as specified. 105

7. The combination with a time-movement, of time-movement stop mechanism and separate time-movement start mechanism connected in an electric circuit closed by the operation of the time-movement, and a control- 110 ling-circuit designed to open the first-named electric circuit, and means for opening or closing the controlling-circuit, substantially as specified.

8. The combination with a time-movement 115 and dial provided with sockets in its face, of an armature provided with a stop-pin de- signed to enter the sockets, a spring for urg- ing the armature toward the dial, and an elec- 120 tromagnet adapted to actuate the armature in opposition to the spring, substantially as specified.

9. The combination with a time-movement and movable dial, of alarm mechanism and stop mechanism actuated successively by said 125 dial, substantially as specified.

10. The combination with a time-movement and dial, of electrically-connected contact- 130 points on the dial, a movable conductor, and an electric circuit between the contact-points

- on the dial and the movable conductor, said electric circuit being closed by the movement of the dial, and stop mechanism brought into operation by said dial, substantially as specified. 5
11. The combination with a time-movement and movable dial, of stop mechanism and alarm mechanism in electric circuit with the stop mechanism, said circuit being closed and 10 said stop mechanism being actuated successively by the movement of said dial, substantially as specified. 75
12. The combination with a time-movement, of time-movement stop mechanism, separate 15 time-movement start mechanism and alarm mechanism actuated, respectively by the operation of the time-movement, substantially as specified. 80
13. The combination with a time-movement, 20 and time-movement stop mechanism, of time-movement start mechanism and alarm mechanism electrically connected, respectively with the stop mechanism, said stop mechanism being actuated by the operation of the 25 time-movement, substantially as specified. 85
14. The combination with a time-movement and stop mechanism, of separate start mechanism and alarm mechanism electrically connected, respectively with the stop mechanism through a start-circuit and alarm-circuit, 30 said stop mechanism being actuated to close said circuits by the operation of the time-movement, and an electromagnet for actuating the stop mechanism to open the start-35 circuit, substantially as specified. 90
15. The combination with a time-movement and stop mechanism, of separate time-movement start mechanism and alarm mechanism in electrical connection respectively with the 40 stop mechanism through a start-circuit and alarm-circuit, a controlling-circuit controlling the movement of the stop mechanism, and means for opening or closing the controlling-circuit, substantially as specified. 95
16. The combination with a time-movement, 45 of stop and start mechanism simultaneously actuated by the time-movement, substantially as specified. 100
17. The combination with a time-movement 50 and dial, starting mechanism and stopping mechanism in electric circuit, said stop mechanism being actuated, and said circuit being simultaneously closed to actuate the starting mechanism by the movement of said dial, substantially as specified. 105
18. The combination with a time-movement and dial, of starting mechanism in electric circuit, alarm mechanism in electric circuit, and stop mechanism adapted to stop the movement of the dial and to open or close the start-circuit and alarm-circuit, respectively, 60 substantially as specified. 115
19. The combination with a time-movement and movable dial, of starting mechanism and 65 alarm mechanism in electric circuit, respectively, said circuits being closed by the movement of the dial, substantially as specified. 120
20. The combination with time-movement and movable dial, of starting mechanism and alarm mechanism in electric circuit, respectively, both circuits being closed by the movement of the dial, the alarm-circuit being opened by the movement of the dial, and means for opening the starting-circuit, substantially as specified. 70
21. The combination with a time-movement and electrically-controlled starting mechanism and alarm mechanism, of a movable part, as for instance, an armature constituting a part of both the starting-circuit and alarm-circuit, and means for actuating the movable part to open or close said circuits, substantially as specified. 75
22. The combination with a time-movement, start and stop mechanism in electric circuit, 80 and a separate circuit controlling the electrical connection between the start and stop mechanism, and means for opening or closing the last-named circuit, substantially as specified. 85
23. The combination with a time-movement and movable dial, starting mechanism, alarm mechanism, a starting-circuit and an alarm-circuit, of an armature adapted to make and break the start-circuit and alarm-circuit, an electromagnet controlling the movement of 90 said armature, a controlling-circuit, and means for opening or closing the same, substantially as specified. 95
24. The combination with a time-movement, 100 its balance-wheel and time-movement stop mechanism, of a movable piece having a flexible extension adapted to brush against the periphery of the balance-wheel to start the same, means for actuating the movable piece, 105 and means for retracting the movable piece after the stop mechanism has been actuated to stop the time-movement, substantially as specified. 110
25. The combination with a time-movement, 110 its balance-wheel and time-movement stop mechanism, of a spring-actuated armature, a flexible extension thereon adapted to brush against the periphery of the balance-wheel to start the same, and a magnet for retracting 115 the armature, magnetized simultaneously with the actuation of the stop mechanism to stop the time-movement, substantially as specified. 120
26. The combination with a time-movement 120 and movable piece adapted to engage and release the same, of an armature adapted to impart an initial impulse to the balance-wheel of the time-movement, a magnet in electric circuit with the movable piece, said circuit 125 being adapted to be made and broken by the movement of the said movable piece, substantially as specified. 130
27. The combination with a time-movement, 130 of an armature adapted to engage and disengage the same, a magnet for actuating the armature, a balance-wheel-starting armature and magnet, means for making an electric circuit through the last-named magnet and

the first-named armature, and make-and-break contact mechanism in said circuit actuated by the first-named armature, substantially as specified.

5 28. The combination with a time-movement and insulating dial provided with a plurality of contact-points and sockets, of a spring-actuated piece, as for instance the armature 14 in operative relation with the contact-points upon and the sockets in the dial, and an alarm-circuit in electrical connection with the contact-points and the movable piece, substantially as specified.

10 29. The combination with a time-movement and dial provided upon its face with a plurality of raised contact-points and sockets, of an armature provided with a stop-pin adapted to make and break contact with one of the contact-points and to thereafter enter 20 one of the sockets, substantially as specified.

15 30. The combination with a time-movement and disk provided with contact-points and sockets, of an armature in operative relation to the contact-points and sockets, an alarm-circuit in electrical connection with the contact-points and armature, a magnet in operative relation with the armature, a controlling-circuit, and means for opening or closing the same, substantially as specified.

20 31. The combination with a time-movement and dial provided with contact-points and sockets, of an armature in operative relation to the contact-points and sockets, an alarm-circuit in electrical connection with the contact-points and armature, a controlling-circuit, and a magnet therein adapted to actuate the armature, a track provided with terminal contact-plates, and a trolley adapted to make and break electrical connection between the plates, substantially as specified.

25 32. The combination with a time-movement and dial provided with contact-points and sockets, of an armature hinged at one end and provided at its opposite end with a stop-pin designed by the movement of the dial to make contact with one of the contact-points and to thereafter enter one of the sockets to stop the time-movement, said armature being spring-actuated in one direction, and a controlling-circuit and magnet designed to actuate the armature in opposition to the spring, means for opening or closing the controlling-circuit, and an alarm-circuit in electrical connection with the contact-points upon the dial 50 and with the armature, substantially as specified.

33. The combination with a time-movement, start mechanism in operative relation thereto, means for actuating the start mechanism, 60 stop mechanism designed to stop the time-movement, and a magnet in electric circuit designed to retract the starting mechanism, and means for closing said circuit to retract the starting mechanism after the stop mechanism has been actuated to stop the time-movement, substantially as specified.

65 34. The combination with a time-movement

and its balance-wheel, of an armature provided with a flexible extension in operative proximity to the balance-wheel, a spring for 70 actuating the starting mechanism, and a starting-circuit designed when closed to cause the retraction of the starting mechanism, said circuit being closed by the operation of the time-movement, substantially as specified. 75

35. The combination with a time-movement, stop mechanism operatively connected therewith, and a spring-actuated armature in operative relation with the time-movement, of a magnet in operative relation with the armature, and a starting-circuit including said magnet, said starting-circuit being closed simultaneously with the actuation of the stop mechanism whereby the time-movement is held stationary while the armature is electrically retracted, substantially as specified. 80

36. The combination with a time-movement, starting mechanism in operative relation thereto, means for actuating the starting mechanism to start the time-movement, stop 90 mechanism, and a magnet in operative relation with the starting mechanism and in electric circuit with the stop mechanism, said stop mechanism being designed to close the circuit to retract the starting mechanism 95 while the time-movement is at rest, a controlling-circuit designed to control the movement of the stop mechanism, and means for opening or closing the controlling-circuit, substantially as specified. 100

37. The combination with a time-movement and dial provided with sockets, of an armature provided with the stop-pin adapted to enter the sockets, starting mechanism in operative relation with the time-movement, said 105 starting mechanism and armature being in electric circuit, and a controlling-circuit including a magnet adapted to actuate the armature, and means for opening or closing the controlling-circuit, substantially as specified. 110

38. The combination with a time-movement and dial provided with sockets, of an armature provided with a stop-pin designed to engage the sockets, starting mechanism in operative relation with the time-movement, means for actuating the starting mechanism to start the time-movement, and a magnet in electric circuit with the armature, said circuit being closed by the movement of the 115 armature when the same is actuated to stop the time-movement, and a magnet and controlling-circuit adapted to actuate the armature, substantially as specified.

39. The combination with a time-movement 120 and dial provided with sockets, of an armature provided with a stop-pin adapted to engage the sockets, a second armature provided with a flexible extension in operative relation with the balance-wheel of the time-movement both of said armatures being spring actuated in one direction and electrically actuated in the opposite direction, substantially 130 as specified.

40. The combination with a time-movement and dial provided with sockets, of an armature provided with a stop-pin adapted to engage the sockets, a second armature in operative relation with the time-movement both of said armatures being spring-actuated in one direction and electrically actuated in the opposite direction, the movement of the first-named armature opening or closing the electric circuit controlling the movement of the armature in operative relation with the time-movement, substantially as specified.
41. The combination with a time-movement and dial provided with sockets, of an armature provided with a stop-pin designed to enter the sockets, a second armature provided with a flexible extension in operative relation with the balance-wheel of the time-movement both of said armatures being spring-actuated in one direction and electrically actuated in the opposite direction, and said armatures being electrically interdependent, substantially as specified.
42. The combination with a time-movement and dial provided with sockets and contact-points, of a starting-circuit and an alarm-circuit in electric circuit with the contact-points, and an armature provided with a stop-pin adapted to make contact with the contact-points and to enter the sockets, said armature being designed to open or close the alarm-circuit and starting-circuit, respectively, substantially as specified.
43. The combination with a time-movement and dial provided with sockets and contact-points, of an armature provided with a stop-pin adapted to make connection with the contact-points and to enter the sockets, an alarm-circuit in electrical connection with the contact-points and the armature, starting mechanism in operative relation with the time-movement and in electric circuit with said armature, substantially as specified.
44. The combination with a time-movement and dial provided with sockets and contact-points, of an armature provided with a stop-pin designed to make contact with the contact-points and to enter the sockets, an alarm-circuit in electrical connection with the contact-points, an armature, and a second armature in operative proximity to the time-movement spring-actuated in one direction, and a magnet in electrical circuit with the first-named armature adapted to retract the spring-actuated armature in operative proximity to the time-movement, substantially as specified.
45. The combination with a time-movement and dial provided with contact-points and sockets, of an armature provided with a stop-pin adapted to make contact with the contact-points and to enter the sockets, an alarm-circuit in electrical connection with the contact-points, an armature, a second armature having a flexible extension in operative proximity to the balance-wheel of the time-movement, and a magnet adapted to actuate said

last-named armature and in electric circuit with the first-named armature, substantially as specified.

46. The combination with a time-movement and dial provided with contact-points and sockets, of an armature provided with a stop-pin adapted to make contact with the contact-points and to enter the sockets, an alarm-circuit in electrical connection with the contact-points and with the armature, a second armature provided with a flexible extension in operative proximity to the balance-wheel of the time-movement, a spring for actuating said armature to impart an impetus to said balance-wheel, and a magnet adapted to retract the last-named armature, substantially as specified.

47. The combination with a time-movement and dial provided with contact-points and sockets, of an armature provided with a stop-pin adapted to make contact with the contact-points and to enter the sockets, an alarm-circuit in electrical connection with the contact-points and with the armature, a spring for actuating the armature in one direction, and a magnet for actuating the armature in opposition to the spring and included in a controlling-circuit, and a second armature provided with a flexible extension in operative proximity to the balance-wheel of the time-movement, a spring for actuating said armature in one direction, a magnet designed to actuate the last-named armature in opposition to the spring and included in a starting-circuit in electrical connection with the first-named armature, substantially as specified.

48. The combination with a time-movement and dial provided with sockets in its face, of an armature provided with a stop-pin adapted to enter the sockets, and means for holding the armature against the face of the dial during the rotation of the latter whereby the stop-pin is forced to enter the socket the instant the same is brought into position by the movement of the dial, substantially as specified.

49. The combination with a time-movement and dial provided with sockets, of an armature provided with a stop-pin designed to be held against the face of the dial during the rotation of the latter, a spring for holding the armature against the face of the dial and for forcing the stop-pin into the socket, a controlling-circuit including an electromagnet for disengaging the stop-pin from the socket, and means for opening the circuit and for closing the same immediately after the stop-pin has been withdrawn from the socket whereby the stop-pin is permitted to rest against the face of the dial during the succeeding operation of the time-movement, substantially as specified.

50. The combination with a time-movement and stop mechanism, of a magnet included in a controlling-circuit and designed to actuate the stop mechanism, and a plurality of separate independent circuit-closing devices in

the controlling-circuit either of which may completely close the controlling-circuit, substantially as specified.

51. The combination with a time-movement and dial provided with sockets at varying intervals, of an armature provided with a stop-pin designed to engage the sockets, a controlling-circuit including a magnet designed to actuate the armature, and a plurality of 10 separate circuit-closing devices any of which are capable, independent of any other, of completely closing the controlling-circuit whereby each circuit-closing device may retract the armature from any particular socket 15 or sockets for the purpose specified, substantially as set forth.

52. The combination with a time-movement, stop mechanism and alarm mechanism, of a magnet and controlling-circuit, and a plurality 20 of circuit-closing devices in the controlling-circuit any one of which may be actuated independent of any other to completely close the controlling-circuit.

53. The combination with a time-movement 25 stop mechanism and time-movement start mechanism electrically interdependent, of a controlling-circuit designed to make and break electrical connection between the start mechanism, and stop mechanism and a plurality 30 of circuit-closing devices in the controlling-circuit, any one of which devices may be actuated to completely close the controlling-circuit independent of any other of said circuit-closing devices, substantially as specified.

54. The combination with a time-movement, of time-movement stop mechanism, separate time-movement start mechanism and alarm mechanism, said start mechanism and said 40 alarm mechanism being respectively electrically interdependent with the stop mechanism, substantially as specified.

55. The combination with a time-movement, of stop mechanism, separate start mechanism 45 and alarm mechanism, said start mechanism

and alarm mechanism being electrically interdependent with the stop mechanism, a controlling-circuit controlling the stop mechanism, and means for opening or closing the controlling-circuit, substantially as specified.

50

56. The combination with a time-movement and stop mechanism, of separate start mechanism and alarm mechanism electrically interdependent, respectively with the stop mechanism, and a controlling-circuit for controlling the stop mechanism provided with a plurality of circuit-closing devices any one of which may be actuated to completely close the controlling-circuit, substantially as specified.

55

57. The combination with a time-movement, 60 an insulating rotating disk and contact-maker, of a plurality of contact-points upon the disk electrically connected with each other and with the contact-maker through an electric circuit, substantially as specified.

65

58. The combination with a rotating disk provided with a plurality of contact-points electrically connected with each other, a contact-maker also included in the electric circuit, and mechanism upon the contact-maker 70 and disk adapted to co-operate to stop the movement of the disk, substantially as specified.

70

59. The combination with a time-movement and stop mechanism, of separate start mechanism 75 electrically interdependent with the stop mechanism, a controlling-circuit controlling the movement of the stop mechanism, a plurality of tracks provided with insulated contact-plates within the controlling-circuit, 80 and a trolley designed to make contact between the contact-plates and close the controlling-circuit, substantially as specified.

In testimony of all which I have hereunto subscribed my name.

GEORGE FREDERICK BRACKETT.

Witnesses:

JAMES WATSON,
J. FRED. KELLEY.
